US00D448976B1

(12) **United States Design Patent** (10) Patent No.: **US D448,976 S**
 McDonough et al. (45) Date of Patent: ** Oct. 9, 2001

(54) **PINCHED TRAINER CUP**

97711	8/1987 (AU).
595296	9/1987 (AU).
98916	12/1987 (AU).

(57) **CLAIM**

The ornamental design for a pinched trainer cup, as shown.

DESCRIPTION

FIG. 1 is a perspective view of a pinched trainer cup showing the new design;

FIG. 2 is a front elevational view thereof;

FIG. 3 is a rear elevational view thereof;

FIG. 4 is a right side elevational view thereof;

FIG. 2 is a left side elevational view thereof;

FIG. 6 is a top plan view thereof; and,

FIG. 7 is a bottom plan view thereof.
